UNITED STATES PATENT OFFICE.

ARTHUR C. ROWLEY, OF PHILADELPHIA, PENNSYLVANIA, ASSIGNOR TO ASSOCIATED AUTOMATIC SPRINKLER CO., OF PHILADELPHIA, PENNSYLVANIA, A CORPORATION OF DELAWARE.

FUSIBLE LINK.

1,174,353.

Specification of Letters Patent.

Patented Mar. 7, 1916.

Application filed January 6, 1915. Serial No. 754.

To all whom it may concern:

Be it known that I, ARTHUR C. ROWLEY, a citizen of the United States, and a resident of the city of Philadelphia, county of Philadelphia, and State of Pennsylvania, have invented certain new and useful Improvements in Fusible Links, of which the following is a specification, reference being had to the accompanying drawing.

10 My invention relates primarily to a link suitable for use with automatic sprinklers for fire extinguishing apparatus or other devices wherein it is desirable to hold certain parts of the mechanism in positive relation until the temperature in the vicinity of the apparatus reaches a point sufficient to cause the softening of a fusible binding material uniting the parts of the link to permit the separation thereof to release the mechanism to which the link is applied.

15 Among the principal objects of my invention are to provide a fusible link which shall be positive and efficient in operation and in which a positive separation of the members thereof will instantly take place as soon as the temperature in the vicinity of the link is raised sufficiently to cause the melting of the fusible material which serves to secure the members of the link in assembled relation.

20 Further objects of my invention are to provide a fusible link which shall comprise a minimum number of parts, which may be cheaply and readily constructed, and which shall be so designed as to minimize the strain upon the fusible material which serves to normally unite the parts of the link.

25 My invention further includes all of the other various novel objects and features of construction and arrangement hereinafter more definitely specified.

30 In the accompanying drawing is illustrated a fusible link constructed in accordance with one embodiment of my invention, 45 Figure 1 showing a side elevation of the link in operative position upon fragmentary portions of the lever arms of an automatic sprinkler; Fig. 2 a central vertical section of the link removed from the arms; Fig. 3 50 a perspective view of the two members composing the link and separated from each other; Fig. 4 a similar view of the members in partially assembled position, and Fig. 5 a fragmentary front elevation of one of said members.

35 That form or embodiment of my invention illustrated in the drawing comprises a pair of members A and B, the said members being in all respects identical with each other, and being assembled, as hereinafter described, to form the completed link. Considering either of the said members, for example, member A, the same may consist of a flat body portion, preferably substantially rectangular in form and having a suitable 45 integral lug 2 extending outwardly from its upper extremity, when viewed in the position shown in Fig. 3, preferably substantially semi-circular or elliptical in form provided with a suitable aperture 3 suitable 50 for the reception of the hooked levers 5 with which the sprinkler head, or other device to which the link is designed to be operatively attached, may be provided.

55 The member may preferably be formed 75 from suitable sheet metal of substantially constant thickness, and may be provided adjacent the upper and lower extremities of the body portion, still considering the member A as shown in Fig. 3, with pairs of 80 spaced ears 8 and 9, the ears all being preferably of equal size, and the upper pair of ears 8 extending from adjacent the side edges 10 of the lug 2 where it joins the body 1 to the side edges 12 thereof, the outer side 85 edges of the ears being preferably coincident therewith, and the pair of ears 9 preferably extending downwardly from the lower edge of the body portion 1 and inwardly from the side edges 12 thereof along said lower 90 edge, so that, as the said ears 9 are identical in size with the ears 8, a space will be left between the inner edges of said ears 9 along the lower edge of the body 1 substantially equal in width to the width of the lug 2 95 where it joins the body. The ears are preferably slightly beveled on their inner edges from their points of juncture with the body portion to their extremities and toward the side edge 12 of the body so that a small, 100 substantially V-shaped clearance 15 will be formed between the inner edges of the ears and the side edges 10 of the lug 2 between the ears 8 and the lug, while the sides of the opening formed between the ears 9 and the lower extremity of the body will be slightly 105 outwardly divergent, as best shown in Fig.

110 5. Each pair of ears, moreover, is preferably bent from the plane of the body 1 along lines substantially coincident with the up-

per and lower extremities thereof substantially 45° from the plane of the body, but in opposite directions therefrom, so that, still considering member A in Fig. 3, the 5 upper pairs of ears 8 will extend forwardly at substantially 45° from the vertical and the lower set of ears 9 will extend rearwardly at a similar angle, whereby the two pairs of ears will lie in substantially parallel 10 planes, but extend in opposite directions from the body. The angle at which the ears are bent from the plane of the body may, however, be varied as desired.

The body of each member is preferably 15 provided with a plurality of projections or ridges 20 and 21, which are struck up from the body in such manner that they extend in opposite directions, the ridge 20 in member A of Fig. 3 extending forwardly and the 20 ridge 21 rearwardly beyond the surfaces of the body. These ridges preferably extend parallel to the upper and lower extremities of the body for a considerable distance across the face thereof, and are preferably 25 so proportioned that the exterior dimensions of the smaller ridge 21 will be substantially similar to the interior dimensions of the larger ridge 20, and are so disposed with relation to the body that when the members 30 are assembled to form the completed link as hereinafter described, the exterior of the smaller ridge will be adapted to fit or "nest" within the interior of the larger. It will be understood that while but two ridges are 35 illustrated in the drawing, a greater number may be employed if desired and the size and configuration of the ridges may also be varied as required.

The members of the link which, as hitherto 40 stated, are preferably identical in all respects, may be formed in any suitable or convenient manner as by stamping the same from suitable sheet metal, the ridges being formed thereon either during the same operation or by another subsequent operation by means of suitable dies, or otherwise, and the ears also being given their proper inclination by suitable means. The completed link, comprising a pair of the members, may 45 now be assembled by inverting and reversing one of the members from the position shown at A in Fig. 3 to the position shown at B in the same figure, and then bringing the two members together, as shown in Fig. 50 4, with their side edges 12 coincident, in which position the smaller ridge 21 upon either member will rest within the large ridge 20 upon the opposing member and the lug 2 upon either member project between the ears 9 on the opposing member. In this position the members may be secured together by suitable fusible metal or solder 55 spread, by any suitable and convenient means between the opposed faces of the body portion and the ears as best shown in

Fig. 2. The link is now assembled and in condition to be attached to the sprinkler head or other apparatus with which it is designed to be employed, as shown in Fig. 1, and will remain in assembled relation thereon to maintain the parts thereof, as levers 5, in positive normal relation until the temperature in the vicinity of the link is raised above the melting point of the fusible material 25, which will cause the material to 70 give way and the members of the link to instantly separate, the strain exerted by the arms 5, or other devices to which the link may be attached, causing the surfaces of the smaller ridges to ride along the surfaces of 80 the interior of the larger ridges and then upon and along the adjacent surfaces of the bodies of the members, thus tending to force the members apart in a direction substantially normal to the direction of the strain 85 exerted by the arms, and counteracting any tendency toward a delayed separation of the members owing to adhesion arising from incomplete fusing of the fusible material or other causes. 90

It will be evident that while the link is assembled and in normal position upon the hooks 5, or other device to which it is attached, a large portion of the strain exerted by the arms will be diverted from the fusible 95 material 25 between the members and transferred to and absorbed by the bent ears 8 and 9, as well as by the ridges in the bodies of the members, thus tending to prevent any "creeping" of the members due to the weakness of the fusible material itself, whereby the members will be held firmly in their proper assembled relation until the fusible metal is melted or materially softened by a sufficient increase in temperature in the 100 vicinity of the link. It will also be evident that owing to the clearance space 15 between the ears and edges of the lugs, no resistance to the instant separation of the members of the link can arise by reason of 105 any friction between the lugs and the ears owing, for instance, to a slight disalignment of the members of the link in assembling, or from other causes, and which might tend to retard the instantaneous separation of the 110 members. It will furthermore be evident, while I have illustrated the link in Fig. 1, in operative position upon the fragmentary portions of the arms of a sprinkler head, tending normally to separate under the pressure of the fluid within the sprinkler system, and which tendency is normally resisted by the operation of the link, that my improved link is equally adapted for use in connection with mechanisms having parts 115 tending normally to close together instead of to separate, and that when used in connection with such devices, the link will normally be under compression instead of under tension and will serve to maintain the parts 120 125 130

in fixed relation until the fusing of the material 25, when the members A and B will immediately separate, as heretofore described, and permit the parts to which they may be attached to move toward each other to effect the purposes of the device.

While I have illustrated and described herein but one form of my improved link, I do not desire to limit myself specifically to that embodiment of the device, as it will be evident that various changes may be made in the details of construction and arrangement of the various parts thereof without departing from the spirit and scope of the invention as defined in the appended claims.

Having thus fully described my invention, I claim and desire to protect by Letters Patent of the United States:

1. A fusible link comprising a plurality 20 of similar members, each of said members comprising a body portion and a plurality of ears adjacent opposite extremities thereof, projecting beyond said body portion in angular relation therewith and in substantially parallel planes.

2. A fusible link comprising a plurality 30 of similar members, each of said members having a body portion and a plurality of pairs of ears projecting outwardly therefrom and in angular relation therewith, and a plurality of struck up ridges in said body portion projecting in opposite directions above the surfaces thereof.

3. A fusible link comprising a plurality 35 of similar members, each of said members having a substantially rectangular body portion and a pair of ears projecting beyond either end of said body portion, one of said pairs of ears being turned from the plane of said body portion in one direction and the other pair of ears being turned from said plane in the other direction, and a lug projecting outwardly from said body portion between one of said pairs of ears.

4. A fusible link comprising a plurality 45 of similar members, each of said members having a substantially rectangular body portion and a pair of ears projecting beyond either end of said body portion, one of said pairs of ears being turned from the plane of said body portion in one direction and the other pair of ears being turned from said plane in the other direction, a lug lying in the plane of said body portion and projecting outwardly therefrom between one of said pairs of ears, and a plurality of struck up projections extending in opposite directions above the surfaces of said body portion.

5. A fusible link comprising a pair of 60 oppositely and inversely disposed similar members, each of said members having a substantially rectangular body portion and a pair of outwardly projecting ears upon opposite extremities thereof, each of said

pairs of ears being bent from the plane of said body portion and extending in opposite directions therefrom, and in substantially parallel planes, a lug projecting between one of said pairs of ears, and a plurality of 70 struck up ridges extending beyond the surfaces of said body and in opposite directions therefrom, said ridges being so disposed upon said member as to rest within or contain corresponding ridges upon the 75 other of said members when said members are assembled to form the completed link.

6. A fusible link comprising a pair of inversely and oppositely disposed similar members, each of said members having a 80 substantially rectangular flat body portion having a pair of outwardly projecting ears at either extremity, each of said ears being outwardly beveled toward its end, a lug extending outwardly from said body portion 85 between one of said pairs of ears and having an opening, and fusible material operative to secure said members in fixed relation.

7. A fusible link comprising a pair of 90 inversely and oppositely disposed similar members, each of said members having a substantially rectangular flat body portion having a pair of outwardly projecting ears at either extremity, one pair of said ears 95 being bent from the plane of said body for substantially 45° in one direction, and the other pair of said ears being similarly bent in the opposite direction, and each of said ears being outwardly beveled toward its 100 end, a lug extending outwardly from said body portion between one pair of said ears and having an opening, a plurality of struck up ridges projecting above the surfaces of said body portion and so disposed as to 105 align with the corresponding ridges of the other of said members when said link is assembled, and fusible material operative to secure said members in fixed relation.

8. In a fusible link, a member comprising 110 a body portion and a pair of ears projecting beyond each of two opposed extremities thereof, each pair of ears being respectively bent from the plane of said body portion in a direction opposite to that of the other 115 pair.

9. In a fusible link, a member comprising a body portion and a pair of ears projecting beyond each of two opposed extremities thereof, said ears being bent from the plane 120 of said body portion in opposite directions and outwardly beveled toward their ends, and a plurality of projections struck up from said body portion and extending in opposite directions therefrom.

10. In a fusible link, a member comprising a body portion having an outwardly extending lug, a pair of ears disposed on either side of said lug, a second pair of ears disposed opposite said first mentioned pair 130

with relation to said body and spaced from each other for a distance corresponding to the width of said lug.

11. In a fusible link, a member comprising a substantially flat body portion having an outwardly extending lug having an aperture, a pair of ears disposed on either side of said lug, a second pair of ears disposed opposite said first mentioned pair with relation to said body and spaced from each other for a distance corresponding to the width of said lug, each of said pairs of ears being bent in opposite directions from the plane of said body, and a plurality of 15 struck up projections extending beyond the surface of said body.

12. In a fusible link, a member comprising a body portion and ears disposed in angular relation therewith adjacent each of

two of its respectively opposite extremities and in substantially parallel planes.

13. A fusible link comprising a pair of similar members each having a body portion and ears extending beyond each of two of the opposite extremities thereof in angular 25 relation therewith and in substantially parallel planes, said members being assembled in respectively inverse and reverse relation and normally united by fusible material.

In witness whereof, I have hereunto set my hand this 5th day of January, A. D., 1915.

ARTHUR C. ROWLEY.
